UNITED STATES PATENT OFFICE.

IRA A. WEAVER, OF SPRINGFIELD, ILLINOIS, ASSIGNOR TO WEAVER MANUFACTURING COMPANY, OF SPRINGFIELD, ILLINOIS, A CORPORATION OF ILLINOIS.

ANVIL BLOCK.

Application filed November 3, 1920. Serial No. 421,478.

To all whom it may concern:

Be it known that I, IRA A. WEAVER, a citizen of the United States, residing at Springfield, in the county of Sangamon and 5 State of Illinois, have invented certain new and useful Improvements in Anvil Blocks, of which the following is a specification.

Automobile wheel rims are of various forms and styles, clincher, straight side, etc., 10 and in service and during the changing of tires and rims they are subject to numerous types of injuries and deformations requiring correction. All parts of such several shapes of rims are likely to be damaged, 15 and those, for example which have grooves along their outer edges for the accommodation of locking rings, are more or less easily injured by a hammer blow while tires are being changed, which damage makes it 20 impossible for the ring to be properly seated in the groove until the bent part is trued up. Transversely split rims usually have locking means or catches riveted thereto near their meeting ends and these not infrequently are broken off necessitating repair.

Accordingly, my invention relates to form-blocks or anvils especially designed and adapted for use in the truing, shaping, 30 and repair of such injured vehicle wheel rims, whether they are permanently affixed to their wheels or whether they are of the well-known demountable type.

One of the objects of the invention is, 35 therefore, the provision of a block or anvil intended to be attached to and to overhang from a bench or other suitable support, such projecting part, as well as that above the bench or table, being employed in the 40 straightening or truing operation and otherwise working on the several forms of rims.

In case the damaged rim, such as one which has been injured or bent by a hammer blow, is not demountable from its wheel, the 45 latter with the rim may be brought to the block or anvil and trued or repaired by the use of a suitable tool or tools, or the block may be removed from the bench and applied to the rim and held in position by hand 50 while the rim is being straightened without removing the wheel from the vehicle.

To enable the public to understand the structural characteristics of an anvil block embodying this invention a preferred and 55 desirable embodiment of the same has been

illustrated in the accompanying drawings forming a part of this specification to which reference should be had in connection with the following detailed description and throughout the several views of which drawings like reference characters refer to the same parts.

In these drawings:

Figure 1 shows such an anvil block in plan view applied to a bench or other appropriate support;

Figure 2 is a central, longitudinal, vertical section through the appliance shown in Figure 1;

Figure 3 is an end view of the block applied to a bench and viewed from the overhanging end;

Figures 4 and 5 illustrate in perspective types of tools adapted for advantageous employment in connection with such anvil 75 blocks;

Figure 6 shows the use of the block or anvil for the straightening or truing of the flange of a rim forming a permanent part of a wheel;

Figure 7 illustrates the overhanging part of the anvil block used in connection with the repairing of a demountable rim of the quick detachable type;

Figure 8 depicts the employment of the 85 block in connection with a clincher rim;

Figure 9 shows the improved form block used for straightening a flange of a straight side rim; and

Figure 10 portrays the employment of the 90 block with a clincher rim forming a permanent part of its wheel.

By reference to these drawings, it will be seen that the improved anvil or block, forming the subject matter of this invention, has a flat bottom surface 20 adapted to rest on a bench or other appropriate support 21 to which it may be conveniently fastened by one or more screws or bolts 22, 23 extended through registering holes in the 100 two members. The bottom of the anvil or form block is desirably provided with a cross rib or projection 24 adapted to bear against the edge of the bench to position the block thereon with the proper portion of the later overhanging the edge of the bench and to prevent the block from being applied to the support incorrectly end for end.

The top face 25 of the end section of the 110 cutting or projecting part of the anvil or

block is transversely curved or upwardly bowed to practically conform to the inner surface of a wheel rim of average diameter, such for example, as one of the quick detachable type permanently affixed to its wheel as, for instance, one of the well-known wire wheels. The inner end of this curved surface, which may have a slight depression 26 at this point if desired to more readily accommodate the grooved part of the rim, terminates in a vertical shoulder or wall 27 against which the edge of the rim may bear while being operated upon. Such an employment of the anvil is illustrated in Figure 6, it being observed that the relatively narrow surface 25 permits the block to be used with such a rim without interference with the wheel of which the rim forms a part. Irregularities or indentations in the shape of the rim may be thus removed by the employment of one or more suitable tools, the block itself constituting an anvil or form member assisting in such truing operation.

It will be understood, of course, that if preferred the anvil or block may be detached from the bench and applied to the rim in the manner shown, being held in place by hand during its use. Such employment of the block does not require the wheel being removed from the vehicle while the rim is being straightened.

Where the block and wheel are associated together as illustrated in Figure 6, it may or may not be necessary or desirable to supplement the supporting capacity of the block itself by other means for holding the wheel in position during the work done thereon.

The projecting part of the anvil is also supplied with a similarly curved but more elevated surface 28 wider or broader than the face 25 and having a similar shallow depression 29 adjacent to the upright shoulder or wall 30 against which the edge of the rim may bear. Such portion of the block, as is illustrated in Figure 7, is especially designed or adapted for use with rims of the quick detachable form which are demountable from their wheels, and owing to the absence of spokes and felloes such rims may rest on this surface in a better manner and be more completely supported by the block than could be experienced in attempting to use the narrower section 25 which would perhaps necessitate supplemental means to assist in holding the rim in place. It is, of course, the demountability of such rim from its wheel that permits it to be more readily worked on on this particular part of the block, all as is clearly depicted in Figure 7.

The upwardly projecting section 31 of the block, the outer face of which forms the surface 30 referred to above, has a top flat horizontal face 32 designed to be used as a straightening block and this, as will be observed, is directly above the bench since the

work performed thereon does not necessitate that it possess overhanging characteristics.

The rear face 33 of the part 31 is curved about a vertical center or axis to conform to rims of the average diameter, and adjoining this is a similarly curved groove 34 adapted to receive the lower flange portion of a demountable clincher rim when positioned in a substantially horizontal plane as is depicted in Figure 8. The shape of this groove and the corresponding surface of the part 31 enables the operator by the employment of proper tools to rid such a rim of any irregularities in its proper shape or form.

To the rear of such groove the block has a more elevated transverse rib 35 with a downwardly curved top surface 36 shaped to conform substantially to the outer face of a straight side rim of average diameter, the front and rear faces 37 and 38 of such upstanding part flaring or diverging somewhat to conform practically or in part to the inner surfaces of the flanges of such a straight side rim. The manner of truing the bent flanges of such a rim of this kind is illustrated in Figure 9 and any riveting or repairing required to be done on the lock or catch element of such a transversely-split rim can be performed on the top or curved face 36 all as will be readily understood, the operator working from the inner side of such rim. The vertical rim may be shifted forwardly or rearwardly to bring the one or the other flange against its corresponding face of the block or anvil as will be readily appreciated.

Lastly, to the rear of the part 35 the block is supplied with a groove 39 substantially like the groove 34 and intended to receive the edge portion of a clincher rim permanently fixed to its wheel and which is disposed in a horizontal plane as illustrated in Figure 10 when this groove is employed.

No further explanation of the construction and manner of using the anvil is required, it being apparent from the several illustrations and the above description that a block of this kind may be advantageously used in repairing all of the several styles of rims now on the market.

Those skilled in this art will understand that the invention is not limited and restricted to the precise and exact details of structure shown and described but that these may be modified within comparatively wide limits without departure from the substance and essence of the invention and without the sacrifice of any of its substantial benefits and advantages.

I claim:

1. As an article of manufacture, an anvil block for use with vehicle wheel rims having a curved surface adapted to conform substantially to the curvature of the inner face of a vehicle wheel rim and a shoulder against which an edge of the rim is adapted

to bear when applied to said curved surface, substantially as described.

2. As an article of manufacture, an anvil block for use with a vehicle wheel rim having a curved surface adapted to conform substantially to the curvature of the inner face of a vehicle wheel rim and a shoulder against which an edge of the rim is adapted to bear when applied to said curved surface, the width of said curved surface being such and the position of said shoulder being sufficiently near the end of the block to permit the use of the latter with a rim fixed to its wheel, substantially as described.
- 15 3. As an article of manufacture, an anvil block for use with vehicle wheel rims having a curved surface adapted to conform substantially to the curvature of the inner face of a vehicle wheel rim and a shoulder 20 against which an edge of the rim is adapted to bear when the rim is applied to said curved surface, the latter adjacent to said shoulder having a depression to receive a portion of the rim, substantially as de- 25 scribed.

4. As an article of manufacture, an anvil block for use with vehicle wheel rims adapted to be applied to a support with a portion of the block overhanging from such 30 support, the block on said overhanging part

having a curved surface adapted to conform substantially to the curvature of the inner face of a vehicle wheel rim and a shoulder against which an edge of the rim is adapted to bear when the rim is applied to such 35 curved surface, substantially as described.

5. As an article of manufacture, an anvil block for use with vehicle wheel rims constructed to be secured to a support with a portion overhanging from such support, 40 said block having a curved surface on such overhanging part of less width than and adapted to conform substantially to the curvature of the inner face of a vehicle wheel rim and a shoulder on such overhanging 45 part against which an edge of the rim is adapted to bear when the rim is applied to such curved surface, the latter adjacent to said shoulder having a depression substantially parallel to the shoulder to receive a 50 rib of the rim, substantially as described.

6. As an article of manufacture, an anvil block having a portion curved to conform substantially to the outer face of a vehicle wheel rim and having an adjacent surface 55 simultaneously conforming substantially to at least a part of the flange of the rim applied to said curved surface, substantially as described.

IRA A. WEAVER.
